UNITED STATES PATENT OFFICE.

ALBERT ABBE GRISWOLD, OF PROVIDENCE, RHODE ISLAND, AND ALVIN CARROLL GODDARD, OF RICHMOND HILL, NEW YORK; SAID GODDARD ASSIGNEE, BY MESNE ASSIGNMENTS, TO JOHN FRANCIS CHEVALIER, OF BROOKLINE, MASSACHUSETTS.

WIRE-CUTTING MECHANISM.

Application filed October 22, 1924. Serial No. 745,150.

Our present application is a continuation in part of our United States patent application, filed May 12, 1922, Serial No. 560,481, flexible shingle wiring machine, now 5 United States Patent No. 1,571,582, granted February 2, 1926.

Our invention has reference to an improvement in wire cutting mechanism as applied to machines for manufacturing flexible shingles and more particularly to an improvement in such a machine for manufacturing flexible shingles, being the same as shown in United States Patent No. 1,274,410, granted August 6, 1918, to Albert Abbe 10

15 Griswold, one of the present joint inventors. The object of our invention is to improve the construction of a flexible shingle wiring machine and more particularly to improve the construction of the wire cutting mechanism of such machines.

Our invention consists in the peculiar and novel construction of a flexible shingle wiring machine and more particularly to an improvement in the wire cutting mechanism 20 of a flexible shingle wiring machine, said wire cutting mechanism having details of construction for cutting a wire a predetermined length for a wire staple, as will be more fully set forth hereinafter and claimed.

30 The figures in the drawings illustrate our improved wire cutting mechanism and show adjacent portions of the flexible shingle wiring machine, so that those skilled in the art will understand the same, the major portion 35 of the machine being shown in our United States patent application above referred to.

Figure 1 is a detail vertical sectional view 40 through the wire feed mechanism and the principal parts of the wire cutting mechanism.

45 Figure 2 is a still further enlarged detail sectional view of that part of the wire feed mechanism that grips and feeds the wire into the machine.

Figure 3 is an enlarged detail vertical sectional view similar to Figure 1 showing more in detail the means for operating the wire cutting mechanism, and

50 Figure 4 is a still further enlarged detail face view of the wire cutting plate, the attaching portion of the staple forming slide being shown in section.

In the drawings A indicates a portion of

the frame of the machine, B a crank in the 55 driving mechanism, C the wire feed mechanism, D the wire cutting mechanism, E part of the staple forming mechanism slide and F the wire.

All of the machine not shown in the drawings is the same as shown in our United States patent application referred to and which operates as follows: A depression of a foot treadle will through a clutch operating mechanism allow the driving mechanism 60 to operate, so that the machine will make one complete operation and stop, for each 65 operation of the foot treadle.

The wire feed mechanism C consists of 70 a crank B on the driving shaft operatively connected with a horizontal bar 9 which in turn is operatively connected to a vertical lever 10 on the rear end of a shaft 11 in bearings 12, 12, in a bracket 13, on the frame A. On the forward end of the shaft 75 11 is a vertical lever 14 operatively connected at its lower end to a slide 15 sliding in ways on a horizontal extension 16 of the frame A. The slide 15 has a spring operated arm 17 pivotally connected to a lever 18 80 on a wire gripping member 19, which has a wire gripping jaw 20 and which is pivotally secured to vertical arms on the slide 15, as shown in Figure 5. The wire is gripped 85 between the wire gripping jaw 20 and the top of the slide 15, to feed the wire F into the machine. On the frame extension 16 to the right of the slide 15 is a block 21 and a spring operated wire gripping jaw 22 which allows a free inward movement of 90 the wire and also prevents a retrograde movement of the wire F. To the right of the block 21 and rotatably supported in bearings on the frame extension 16 is a series 95 of wire straightening rolls 23, 23. On the end of the extension 16 is pivotally secured a normally horizontal arm 24 having a bent inner stop end 25 and a bifurcated outer end 26 in which is pivotally secured a grooved pulley 27. The wire F comes 100 from a source of supply, not shown, under the pulley 27, through the straightening rolls 23, 23, under the wire gripping jaws 22 and 20 and then through my improved wire cutting mechanism D.

The staple forming mechanism slide E has a vertical sliding movement in the frame A, and up and down movement for each op-

eration of the machine and it is constructed to have a recess 28 formed by top and bottom lugs 29 and 30 respectively and the frame A has vertical guide-ways 31, 31, as shown in Figure 4.

My improved wire cutting mechanism consists of a hardened steel bushing 32 having a small flat longitudinal wire bore 33 the size and shape of the wire F. The inner 10 end 34 is squared off and forms one of the wire cutting members. This bushing 32 is fixed in the frame A, as shown in Figure 3. The other wire cutting member is in the form of a hardened steel plate 35 held in the 15 recess 28 in the staple forming mechanism slide E of the staple forming mechanism and this plate 35 has a comparatively large round central hole 36 the circular edge of which forms the wire cutting edge of the 20 member.

In the operation of the flexible shingle wiring machine having our improved wire cutting mechanism, the first downward movement of the foot treadle, by the foot of 25 the operator, causes the driving mechanism to be brought into operation to close the clutch members on the driving shaft and the pulley. The driving shaft now makes one complete revolution and then stops. In this 30 first revolution of the driving shaft the wire feed mechanism C feeds a predetermined length of the wire F into the machine.

The operation of the wire feed mechanism C is as follows. In each revolution of the 35 driving shaft the crank B through the horizontal bar 9, the vertical lever 10, the shaft 11, the vertical lever 14, the slide 15, the arm 17, the lever 18, the wire gripping member 19 and the wire gripping jaw 20, 40 operates the slide 15 to draw the slide towards the machine. In this movement of the slide 15 the wire F is gripped between the slide 15 and the gripping jaw 20, and the wire F is fed into the machine the required 45 length for each revolution of the driving shaft. As the wire F is intermittently fed into the machine from a source of supply, not shown, it comes under the straightening 50 pulley 27 then between the straightening rolls 23, 23, which straightens the wire and the wire then goes between the block 21 and the spring operated wire gripping jaw 22. This wire gripping jaw is shaped so as to 55 allow a free passage of the wire into the machine. When the inward movement of the wire stops the wire gripping jaw 22 automatically grips the wire between the wire gripping jaw 22 and the top of the block 21, which is fast to the frame extension 16, 60 and prevents a retrograde movement of the wire.

In the operation of our improved wire cutting mechanism D the hardened steel bushing 32 is fixed in the frame A and the wire F is fed through the small flat bore 65 33 a predetermined length, by the wire feed mechanism C and the staple forming mechanism slide E is given an up and down movement by the mechanism of the machine, for each complete operation of the machine and 70 by the shearing action of the squared off end of the hardened steel bushings 32 and the circular cutting edge of the round central hole 36 in the hardened steel plate 35, the required length of the wire is cut off. 75 By this construction a downward movement of the plate 35 causes the upper curved edge of the cutting hole 36, to cut downward through the flat wire F and the upward movement of the plate 35, causes the lower curved edge of the cutting hole 36, to cut upward through the flat wire F, thereby leaving a clean cut end on the wire F, without burring the end of the wire. 80

Having thus described our invention we 85 claim as new:

1. A wire cutting mechanism comprising a hardened tubular steel wire cutting bushing secured in the frame of a machine and having a small flat wire bore and a squared off wire cutting end, a flat cutting plate having a comparatively large round cutting aperture, the circular edge of the aperture forming a continuous cutting edge larger than the small flat wire bore of the 95 cutting bushing and secured to a slide of the machine and bearing against the squared off wire cutting end of the wire cutting bushing, said slide having up and down movements for the purpose as described. 100

2. A wire cutting mechanism comprising a hardened tubular steel wire cutting bushing secured in the frame of a machine and having a small flat wire bore and a squared off wire cutting end, a flat cutting plate secured to a slide of the machine and bearing against the squared off wire cutting end of the wire cutting bushing, said flat cutting plate having a comparatively large circular wire cutting opening, the upper curved cutting edge of which coacting with the lower flat edge of the flat wire bore in the bushing and the lower curved cutting edge of which coacting with the upper flat edge of the flat wire bore in the bushing, forms the wire 110 cutting edges of the wire cutting mechanism, said slide having up and down movements for the purpose as described.

In testimony whereof, we have signed our names to this specification.

ALBERT ABBE GRISWOLD.
ALVIN CARROLL GODDARD.
